UNITED STATES PATENT OFFICE.

MATHIAS STADTLER, OF CHICAGO, ILLINOIS.

METALLIC SPRING-SUPPORT.

1,324,438.

Specification of Letters Patent

Patented Dec. 9, 1919.

Application filed April 18, 1918. Serial No. 290,942.

To all whom it may concern:

Be it known that I, MATHIAS STADTLER, a citizen of the United States, residing at Chicago, in the county of Cook and State of Illinois, have invented a certain new and useful Improvement in Metallic Spring-Supports, of which the following is a specification.

My invention relates to metallic spring supports adapted for beds, upholstered articles, and the like, and the object of the invention is to provide convenient and practical means for mounting the spring upon metallic cross members in distinction to the ones consisting of webbing. Contributory to this general object it is my purpose to provide means for attaching the base of the spring to the cross members; also to provide cross members which, although made of metal, are resilient within certain limits so as to give the finished article a springy effect, in addition to that which is obtained from the coiled springs alone. Another object is to provide means for deadening the sound when the spring closes up.

I obtain my objects by the construction illustrated in the accompanying drawings in which—

Figure 1 is a perspective view showing the upholstery spring and the supporting means therefor.

Fig. 2 is a sectional view on the line 2—2, Fig. 1, and

Fig. 3 is a perspective view of a hook for securing the foot of the spring to the cross members.

Like numerals denote like parts throughout the several views.

In the form selected to illustrate the invention the spring 1 is of the ordinary coiled type sometimes referred to as an "upholstery spring" and sometimes as a "bed spring." The lower turn of the coil rests upon two cross members 2, 3 at the point of intersection thereof. Said cross members, instead of being strips of webbing, duck or other woven fabric, are of metal. In general shape they are in the form of strips somewhat narrower than the fabric strips commonly used for this purpose in beds and upholstery. While the size is immaterial, I have found by experiment that a strip about $1\frac{1}{2}$ to 2 inches wide serves the purpose to advantage. These strips are arranged crosswise, one set being anchored to the side rails and the other to the end rails of the bed

spring or frame of the upholstered article in any suitable manner.

In the preferred form of invention the strips are not perfectly plain, but are indented with a series of small pockets which render them resilient lengthwise. While the diameter and depth of the pockets may be varied, a suitable effect will be produced by making the pockets of such diameter that two, three or four may be arranged between the margins of the strip. It is not necessary, however, that these pockets or depressions occur at regular intervals or according to any regular or conventional patterns. The depressions may be formed by hammering or by dies.

The lower turn of the spring is secured to the cross strips 2, 3 by means of hooks 4, one of which is shown in perspective in Fig. 3. The hooks are double ended, the larger hook 4^a being adapted to engage the spring itself, and the smaller hook 4^b being adapted to engage the cross strip. For this purpose each cross strip has a series of holes 5 punched therein, spaced at regular intervals. Each hook has an offset 4^c between its ends, the result being that one portion of the hooks near the larger end 4^a will rest upon the top of the cross strips while the other portion will lie beneath the cross strip, and the portion 4^b will pass up through one of the apertures 5 and engage the edge of it. In other words, the construction of the parts is such that one portion of the hook will overlie the strip, will then pass down through one of the holes 5, then pass along beneath the strip until the next hole is reached, whereupon the hook 4^b will pass up through the hole and engage the edge of the strip, thus holding the hook securely in place. The holes 5 are of sufficient dimension, lengthwise of the strip, to permit the lip or hook 4^b to be disengaged from the engaged edge. In practice, the larger hooks 4^a engage the lower turn of the spring, while the remaining portion of the anchoring device extends thence radially outward along the strip, passing down through the first hole it comes to, thence along underneath the strip to the next hole where the hook 4^b passes up through and engages the margin of the hole. When the spring is thus held by four hooks, it will be prevented from moving transversely in any direction. Upholstery springs of any diameter may be employed, for the hooks are adjustable length-

wise of the cross strip and any size may be accommodated. Furthermore the hooks may be so placed as to stretch the bottom turn of the spring—that is, increase its 5 diameter somewhat above normal.

In some cases it is desirable, in order to prevent the spring from making a noise when the turn next to the bottom closes down on to the support, to fasten a disk 10 of wood, wood fiber, or similar material upon the cross strips. Such a disk may be fastened by means of a cotter pin 7 or any other suitable means. Ordinarily, it will be 15 slightly smaller in diameter than the diameter of the lowermost coil of the upholstery spring, and hence will fit within it and at the same time will form a cushion to prevent the metal of the upholstery spring from striking upon the metal of the cross strip. This avoids creating an 20 unpleasant metallic sound when the spring is compressed.

It will be observed that my structure is both durable and sanitary, also that it 25 readily lends itself to quantity production. The structure has another advantage in that it is unnecessary to carry more than one type or size of strip for any and all kinds of 30 beds and upholstered articles, because both large and small springs may be attached by merely adjusting the hooks in the proper holes. Repairs may be easily made because if by any circumstances a strip should become 35 damaged (which is unlikely in view of its durability) that single strip may be renewed without particularly disturbing the rest of the structure.

Having thus described my invention what I claim as new and desire to secure by Letters Patent is:—

1. In combination, a helical bed or upholstery spring, crossed metallic strips for supporting the spring, at least one of the strips having a row of holes extending longitudinally, and a fastener having a hook at each end, one hook adapted to engage in a hole in the metallic strip and the other hook adapted to engage a coil of the spring.

2. In combination, a helical bed or upholstery spring, crossed metallic strips for supporting the spring, each strip having a row of holes arranged longitudinally, and double ended hooks adapted at one end to engage in the holes and at the other end to engage the lower coil of the spring, said hooks being offset between their ends, whereby one portion of the hook may overlie the strip and the other portion underlie it.

3. An upholstery spring mounting comprising crossed sheet metal strips having a multiplicity of shallow indentations impressed in them, a coiled spring located at the intersection of said strips, the strips having apertures, and fasteners having at 65 one end a hook adapted to engage in one of the apertures in a strip, and at the other end a hook adapted to engage a turn of the spring.

4. An upholstery spring mounting comprising crossed sheet metal strips, a helical spring located at the intersection of said strips, each strip having two pairs of holes in it, and four double-ended hooks, the outer end of a hook being adapted to engage the 75 outer hole of a pair, and the body of the hook passing through the remaining hole of the pair, and the remaining end of the hook being adapted to engage a turn of the spring.

5. An upholstery spring mounting comprising crossed sheet metal strips, a helical spring located at the intersection of said strips, each strip having two pairs of holes in it, and four double-ended hooks, the 85 outer end of a hook being adapted to engage the outer hole of a pair, thence pass under the strip to the inner hole of the pair, thence upward through the last mentioned hole, thence in the same direction toward the 90 point of intersection of the strips, and having a hook at the inner end adapted to engage a turn of the spring.

In witness whereof, I have hereunto subscribed my name.

MATHIAS STADTLER.
